SIGN CHANGING APPARATUS

Harry C. Heath, Oakland, Calif.

Application August 20, 1934, Serial No. 740,599

10 Claims. (Cl. 40—36)

This invention relates to automatic sign-changing apparatus as used in stores, waiting rooms, etc., as well as in outdoor advertising, and the objects of the invention are to provide a simple mechanism which will change the signs one after another, work silently, effectively, and not get out of order. Other advantages of the invention will appear in the following description and accompanying drawings.

10 In the drawings Fig. 1 is a perspective view of the apparatus with the outer casing omitted and portions of the construction broken away to better reveal the mechanism.

Fig. 2 is a vertical side view of the mechanism with the forward side of the cabinet and framework omitted, also with portions shown in section, and part of the driving gears dotted to show their relative position.

Fig. 3 is an enlarged fragmentary cross section of Fig. 2 as seen from the line 3—3 thereof.

20 Fig. 4 is a front view in reduced scale showing one of the sign bodies or plates used in the apparatus.

Fig. 5 is an enlarged detail showing the manner in which the chain engages a sign to remove 25 it from viewing position.

Briefly described the invention comprises a cabinet 1 arranged to support a plurality or pack 30 of vertically arranged sign plates 2 each suspended at its upper end by a rod 3 projecting at opposite upper corners of the sign and a pair of endless chains or belts 4 traveling vertically at opposite ends of the cabinet and provided with devices 5 to pick up the forward sign, lift it past 35 the viewing opening 6 of the cabinet, carry it over the other signs and deposit it in the rear of them, so that the next one is successively exposed through the viewing opening.

I am aware that apparatus heretofore used 40 operated broadly in the above manner, but the constructional points involved and which make the present apparatus successful are believed to be new.

The cabinet 1 may be of any material and is 45 preferably mounted on a base 7 in which a driving motor 8 is housed and which is preferably a worm gear reduction motor, as indicated, suspended on springs 9 from supports 10, and has its slow speed shaft 11 connected by means of any desired 50 style of flexible coupling 12 to an extension drive shaft 13 extending to the side of the cabinet and fitted with a pinion 14 engaging a large gear 15 on a sprocket shaft 16 extending across the bottom of the cabinet and carrying at both outer 55 ends a chain sprocket 17, the shaft being rotatably

supported in a suitable frame-work 18 which is mounted on the base 7 and carries all of the operative mechanism.

Frame 18 rises almost to the top of the cabinet and carries another pair of sprockets 19 at its upper end to take the endless chains 4 driven by the lower sprockets 17, but there is no through-shaft on the upper sprockets as they are rotatably carried on suitable stub shafts, bolts or spindles 21 projecting inwardly from the frame, as the 10 space between the sprockets must be kept clear for the passage of the signs.

The sign plates 2 as of Fig. 4 are preferably of rectangular sheets of metal with a horizontal rod 3 along the upper edge projecting a short distance at each side, are hung vertically in pack formation by means of their projecting rods engaging over the upper edges of side plates 22 at opposite sides of the frame 18 and which upper edges 22' form rails which are slanted downwardly toward the viewing opening 6 so that as the forward sign is removed the remaining signs will slide down by gravity and forward so that the next will be in place to be engaged by the chains and removed.

To thus successively engage the signs, devices 5 take the form of blocks of about a quarter of an inch in thickness fixed to the chains in confronting relation at an aligned point and provided with inwardly opening notches 23 into 30 which the ends of the rods 3 are adapted to fall as the chain slowly ascends. This action is best indicated in Fig. 5 wherein the leading end of the block 5 is shown as well tapered off as at 5' so as to always get in front of the first pair of sign 35 pins 3. The chains may move outward to blocks 5 over pin 3 and are resiliently forced back by spring leaves 24 to which blocks of good piano grade of felt 25 are attached and the tension of which blocks against the chains may be determined by adjusting screws 26. The rear sides of the forward strands of chain are preferably guided by blocks of piano felt 27 carried on much stiffer leaf springs 28. This arrangement kills 40 all noise in operation.

Above plates 22 and aligned therewith are two similar plates 29 which are shaped along their outer edges to follow the path of travel of the notches 23 in blocks 5 so that as a sign is picked off the front of the pack the pins 3 will be retained in the notches of the blocks until they ride 50 downward on the rear run of the chains and meet an open slot 30 left between the upper and lower plates and into which the pins 3 fall by gravity 55

due to the weight of the sign, and urge all of the suspended signs forward on the rails 22'.

To prevent displacement of the pins 3 during the transfer of the sign small angle iron guides 5 are arranged along the outer sides of both runs of chain as at 31 and 32, and to guard against the sign in transit (2') being lowered upon the upper edges of the pack of signs, small guards 33 are secured to plates 29 and leaf springs 34 and 10 secured to the forward margins of the frame in a manner to bear on the two vertical margins of the sign plates and resiliently force them rearward. Also small rollers are provided at 35 to hold the sign plates forward until they are raised high 15 enough to clear the guards 33 under the action of the springs.

In order to permit removal or changing of the sign plates the back of the cabinet may be left open or provided with a door 36 hinged as at 37, 20 and the signs may be conveniently lifted in single file up the rear line of the chains and over the upper ends of angle irons 32, it being merely necessary to see that the blocks or lugs 5 are not disposed along the rear run. 25 While I show but one set of carrying lugs for transferring the signs, it is evident that any desired number may be used, and that the time of exposure of the signs to the viewing aperture 6 will be correspondingly shortened. However, with 30 one set of lugs any desired duration of exposure may be had by proper selection of motor speeds and gear ratios.

In Fig. 2 the drive pinion and gear 14 and 17 are partially drawn to show their position relative 35 to adjacent parts.

Attention is directed to the fact that in suspending the pack of sign plates in the manner indicated, the suspension rods being encircled by the sheet metal make a combined thickness which 40 creates a space 38 between each sign so that they do not contact, and hence are not dragged across one another in transferring them, but may be run indefinitely without injury, and hence may consist of matter 39 printed or painted directly on 45 the sheet metal or cardboard plates, or paper prints pasted on. If of cardboard the sign plates may have the upper rods or pins 3 secured in place in any convenient manner. While the thickness created at the upper ends of the signs will cause 50 them to hang with the space 38 between adjacent signs, I also score the opposite lateral margins of each sign thereby producing vertical parallel rearwardly projecting ribs 40 on each sign, which ribs slidably engage the thickness at the top edge 55 of the adjacent sign at two spaced points when the front or exposed sign is drawn upward by the chain, thereby reducing the friction of the sliding sign to the minimum and protecting the printed surface of the sign against defacement. 60 These same ribs are formed on metal holders for cardboard signs, the ribs normally bearing against the forward face of the lateral folded card-retaining margins of the metal holder of the adjacent sign.

65 Also, while I show a pair of chains to carry the signs over to the rear of the pack, it is evident that perforated belts would operate the same and are therefore to be included in my use of the word "chains" in the appended claims.

70 Having thus described my improved construction in an automatic sign-changing apparatus, what I claim is:

1. In a sign-changing apparatus, a plurality of sign plates each provided with projecting pins 75 at its upper corners, rails upon which the signs

are suspended vertically one behind the other, said signs formed to touch at their upper edges only and hang clear of one another, and means for picking the signs one at a time from one side of the pack by engagement with said pins lifting the signs, and depositing same successively at the other side of the pack, said means including a pair of endless traveling chains provided with devices for engaging the pins, rollers against which the margins of the sign roll, and a spring 10 acting on the sign successively to force them toward the opposite side of the pack when past the rollers.

2. In a sign-changing apparatus, a pair of confronting slanted tracks, a plurality of sign 15 plates with laterally projecting pins at their upper corners suspended by the pins resting on the tracks and all tending to move toward the lower ends of the tracks, a pair of vertically disposed endless chains respectively at opposite 20 ends of the suspended pack of sign plates, lugs on the chains arranged and adapted to engage the pins of the lowermost sign and carry it up and over the pack for deposit on the tracks at the rear thereof, and means resiliently urging the 25 chains toward said lowermost sign for engaging said pins.

3. In a sign-changing apparatus, a pair of confronting slanted tracks, a plurality of sign 30 plates with laterally projecting pins at their upper corners suspended by the pins resting on the tracks and all tending to move toward the lower ends of the tracks, a pair of vertically disposed endless chains respectively at opposite ends of the suspended pack of sign plates, lugs on the 35 chains arranged and adapted to engage the pins of the lowermost sign and carry it up and over the pack for deposit on the tracks at the rear thereof, and means including blocks of felt resiliently urging the chains toward said lowermost 40 sign for engaging said pins.

4. In a construction as specified in claim 3, resilient devices bearing upon the opposite sides of the chains in opposed relation to said means.

5. In a sign-changing apparatus of the character described, a frame, a pack of sign plates provided each with projecting pins at its upper margin suspended on said frame one in back of the other, a pair of vertically disposed endless chains at opposite ends respectively of the pack 50 of sign plates, sprockets over which said chains run, means for actuating the sprockets to drive the chains, a pair of lugs on said chains provided with notches to receive the pins of the signs and carry the signs one at a time from the face of 55 the pack to the back of the pack, and means for resiliently urging the chains in direction to insure engagement of the notches with said pins.

6. In a sign-changing apparatus of the character described, a frame, a pack of sign plates 60 provided each with projecting pins at its upper margin suspended on said frame one in back of the other, a pair of vertically disposed endless chains at opposite ends respectively of the pack of sign plates, sprockets over which said chains 65 run, means for actuating the sprockets to drive the chains, a pair of lugs on said chains provided with notches to receive the pins of the signs and carry the signs one at a time from the face of the pack to the back of the pack, means for 70 resiliently urging the chains in direction to insure engagement of the notches with said pins, and guides following the path of travel of the chains holding the pins within said notches until in place at the back of the pack.

7. In a sign-changing apparatus, a generally horizontally extending row of substantially rectangular vertically disposed sign plates each formed adjacent the opposite corners of a horizontal edge with an increased thickness and each plate being provided with a generally vertically extending rib at each lateral margin arranged and adapted to slidably engage the thickened portion at the opposite corners of the adjacent plate upon the end plate, the row being moved vertically to expose a side of the adjacent plate, and means for successively moving the end plate of the row vertically to expose a side of the adjacent plate.
8. In a sign changing apparatus a plurality of sign plates having lateral projections at their upper corners, means for supporting said plates from said projections in a generally horizontally extending row, means for successively engaging the projections of each plate for successively lifting the plates from one end of the row and for carrying the lifted plates over the top of the row to a position at the opposite end of said row, means above said row of plates arranged and adapted to yieldably engage each plate upon its being lifted from the row and to urge the lower end of said plate toward said opposite end of the row independently of normal movement of the
- upper end of the plate during movement of the plate across the row.
9. In a construction as defined in claim 8, guide means adjacent said opposite end of the row positioned to engage each of said successively lifted plates during the movement of each plate across the row for guiding each of said plates to a position at said opposite end of the row.
10. In a sign changing apparatus a plurality of sign plates having lateral projections at their upper ends formed for swingingly supporting said plates from said projections, means for supporting said plates from said projections, means for successively engaging the projections of each plate formed to swingingly suspend said plates from said projections and for successively lifting the plates from one end of the row and for carrying the lifted plates over the top of the row to a position at the opposite end of said row, means above the row of plates arranged and adapted to cause each of the lifted plates to swing on said projections from said projection engaging means in the direction of said opposite end of the row for positioning the lower edge of each successively lifted plate adjacent said opposite end of the row in advance of said plate being carried by said projection engaging means to said opposite end of the row.
